UNITED STATES PATENT OFFICE.

ANDREW NORDLUND, OF GASSAWAY, WEST VIRGINIA.

CURRENT-MOTOR.

No. 908,815.

Specification of Letters Patent.

Patented Dec. 29, 1908.

Application filed June 19, 1908. Serial No. 439,457.

To all whom it may concern:

Be it known that I, ANDREW NORDLUND, a citizen of the United States, residing at Gassaway, in the county of Braxton and 5 State of West Virginia, have invented new and useful Improvements in Current-Motors, of which the following is a specification.

The invention relates to an improvement in current motors, and is particularly 10 directed to a means whereby the pressure generated by the current will automatically control the operation of the motor.

The main object of the present invention is the provision of a current motor including 15 a float and a series of pumps operated directly by the current of the stream in which the float is supported, the pressure generated by the pumps being arranged to directly control the effect of the current on the pump operating 20 mechanism, whereby the motor may be set to limit its power to the desired maximum pressure.

The invention will be described in the following specification, reference being had 25 particularly to the accompanying drawings, in which:—

Figure 1 is a view in elevation, partly in section, of a motor constructed in accordance with my invention. Fig. 2 is a rear elevation of the propelling blades. Fig. 3 is a 30 sectional view of the same. Fig. 4 is a sectional view, partly in elevation, of the compression cylinder. Fig. 5 is a sectional view, partly in elevation, of one of the 35 pumps. Fig. 6 is an inner face view of one of the blade supporting blocks.

Referring particularly to the accompanying drawings, my improved current motor comprises a float 1, of any appropriate type, 40 preferably including a hollow watertight bottom section 2 and walls 3 rising therefrom. Secured upon the bottom is a bracket plate 4 on which is supported a series of motor elements, as pumps 5, which may be 45 in any form and in any desired number. The pistons 6 of the pumps depend below the bracket plate 4 and through a well 7 in the bottom of the float, being connected by links 8 to crank portions 9 of a drive shaft 10.

The shaft 10 is supported in brackets 11 50 depending from and below the bottom of the float at each side of the well opening, said shaft being provided near its relatively rear end with a gear 12. The bracket 11 adjacent 55 the gear end of the power shaft depends below the shaft bearing and forms one of a pair

of drive shaft supporting brackets, the other one 13 of which depends from the float bottom in alignment with and rearwardly from the bracket 11. In the brackets 11 and 13 is 60 mounted a drive shaft 14, the forward end of which projects in advance of the bracket 11 and carries a gear 15 arranged to at all times mesh with the gear 12 on the power shaft.

Upon the rear portion of the drive shaft 14 65 is fixed a collar 16, beyond which said shaft is squared at 17 for the reception of securing blocks 18. These blocks, which are in disk form, are of identical structure and formed on their faces with semicylindrical recesses 70 19 arranged radially of the block and opening through the edge thereof, the inner ends of said recesses communicating with head recesses 20 also of semicylindrical shape in longitudinal section and of greater width and 75 depth than the recesses 19. The respective recesses in the blocks 18 are designed to register to provide housings for the shafts 21 and heads 22 of the propeller blades 23, the formation providing for the convenient insertion and removal of the blades as desired and mounting the blades for independent revolvable movement within the blocks while preventing their disconnection from the blocks. 80 The rear terminal of the drive shaft 14 is reduced and threaded at 24 to receive a nut 25 whereby the blocks 18 are secured in applied position. Each blade is provided adjacent the stem 21 with a laterally extending arm 26, the free terminal of which is through a 85 link 27 connected with a collar 28 freely slidable upon the drive shaft, said collar having an annular recess 29 in which is movably fitted a ring member 30, for a purpose which will presently appear. 90

The pumps 5 are supplied with water from the stream through a suction pipe 31 closed by a strainer end 32 for the usual purpose and communicating through a series of laterals 33 with the respective pumps, whereby 100 the action of the pistons 34 within the pumps will serve to draw water through the suction pipe and into the pump cylinders. Each of the pumps through outlets 35 delivers the water under pressure to a discharge main 36, 105 which in turn leads into a compression cylinder 37, from which cylinder an outlet 38 is utilized to direct the water to any appropriate point of use through any desired pipe connection.

With the blades 23 disposed at the proper angle to the direction of current in the 110

stream it is obvious that said current will impart rotation to the drive shaft 14 and through the medium of the gears 12 and 15 operate the pumps to direct a current of water into the compression cylinder 37. As the motor is intended to be automatic in its operation it is obvious that means must be provided for controlling the pressure of the water delivered from the pumps or in other words controlling the operation of the motor. The compression cylinder 37 is designed primarily to accomplish this result, and for the purpose noted there is arranged within the cylinder in position to receive the pressure from the discharge pipe 36, a piston 39, the stem 40 of which projects through and beyond the relatively rear head of the cylinder, as shown in Fig. 4. The stem is connected to an angle lever 41 pivotally supported through an ear fixed to the cylinder 37, which lever is in turn, through a rod 42, connected to an angle lever 43 pivotally supported on the relatively rear bracket 13, said lever 43 being in turn connected to the ring 30 of the sleeve 28 through the medium of a bar 44, which is preferably guided in an opening formed in a flange of the bracket 13. The controlling means used within the cylinder 37 is a coil spring 45 arranged between the piston 39 and the relatively rear head of the cylinder, said spring operating in opposition to the pressure of water from the discharge pipe 36. The strength of the spring 45, which may be such as desired, will control the pressure developed by the motor, it being understood that when such pressure is exceeded the water from the discharge pipe 36 will cause a relatively rearward movement of the piston 39 within the compression cylinder and through the lever 41, rod 42, lever 43, rod 44, sleeve 28, links 27, and arms 26 revolve the respective blades until their edges are disposed in alinement with the current direction, so that the current is without further effect on said blades so far as operating the apparatus is concerned. Any sudden excess of pressure is thus immediately compensated for, it being understood that the spring 45 may be of such strength as to control the motor and limit its maximum power to that desired for the particular work, so that no matter how strong the current in the stream may be the power derived therefrom may be in any degree up to the maximum power of the stream.

Aside from the details hereinbefore described it is to be understood that the construction of the various parts are not material to the present invention, and that I contemplate the use of any material or the construction of the parts in any sizes which may be found desirable in connection with

the particular use for which the motor is intended.

Having thus described the invention what is claimed as new, is:—

1. A current motor including a propeller, means operated by the propeller for delivering water from the motor under pressure, and means controlled by such pressure for operating the blades of the propeller.

2. A current motor including a float, a series of pumps supported thereby, a propeller supported by the float and operating the pumps, and means controlled by the pressure from the pumps for automatically adjusting the blades of the propeller.

3. A current motor comprising a float, a propeller supported thereby, a series of pumps carried by the float, means arranged between the propeller and pumps for operating the latter in the movement of the former, a compression cylinder receiving the discharge from the pumps, and means controlled by said cylinder for varying the angular relation of the propeller blades with the line of direction of the current.

4. A current motor comprising a float, a series of pumps carried thereby, a propeller adapted to be arranged in the stream and including a series of blades, means for rotatively supporting each of said blades, and means operated by the pressure of the discharge from the pumps for adjusting said blades to vary their inclination relative to the direction of current.

5. A current motor comprising a float, a pump carried thereby, a propeller for operating the pump and including a series of independently movable blades, a compression cylinder arranged to receive the discharge from the pump, a piston within said cylinder, and means intermediate the piston and propeller blades whereby in the movement of the piston the angular relation of the blades to the current may be adjusted.

6. A current motor comprising a float, a pump carried thereby, a propeller for operating the pump and including a series of independently movable blades, a compression cylinder arranged to receive the discharge from the pump, a piston within said cylinder, a spring resisting movement of the piston under the influence of the pump discharge, and means intermediate the piston and propeller blades whereby in the movement of the piston the angular relation of the blades to the current may be adjusted.

In testimony whereof I affix my signature in presence of two witnesses.

ANDREW NORDLUND.
